COMBINATION FOOD AND BEVERAGE BASKET FOR AUTOMOBILES OR THE LIKE

Willis L. Harrold, Mishawaka, Ind.

Application September 11, 1957, Serial No. 47,706

Term of patent 14 years

(Cl. D58—4)

Fig. 1 is a side elevational view of a combination food and beverage basket for automobiles or the like showing my new design;

Fig. 2 is an end elevational view thereof;

Fig. 3 is a top plan view thereof with the top removed;

Fig. 4 is an enlarged cross-sectioned vertical view thereof through the center of Fig. 1;

Fig. 5 is a fragmentary enlarged vertical sectional view thereof taken on line 5—5 of Fig. 3;

Fig. 6 is a fragmentary enlarged vertical sectional view thereof taken on line 6—6 of Fig. 3;

Fig. 7 is a fragmentary enlarged vertical sectional view thereof taken on line 7—7 of Fig. 3.

The basket is shown broken away in Fig. 4 for convenience of illustration.

The side and end not shown are the same as the side and end shown.

I claim:

The ornamental design for a combination food and beverage basket for automobiles or the like, as shown and described.
